ABDOMINAL SUPPORT

Alma I. Sheldon, Jackson, Mich., assignor to S. H. Camp
& Co., Jackson, Mich., a corporation of Michigan

Filed Feb. 16, 1959, Ser. No. 54,618

Term of patent 14 years

(Cl. D20—2)

Fig. 1

Fig. 2

Fig. 1 is a front elevational view of an abdominal support showing my new design;

Fig. 2 is a side elevational view, the opposite side thereto being a mirror image thereof.

The belt effect continues around the back of the support.

I claim:

The ornamental design for an abdominal support, as shown and described.
